HEINRICH TALLA, OF HEILBRONN, GERMANY, ASSIGNOR TO PRÄCISIONSGUSSWERKE SYSTEM SCHMIDT-REICHARDT G. M. B. H., OF FRANKFORT-ON-THE-MAIN, GERMANY.

APPARATUS FOR CASTING METALS.

1,302,450.

Specification of Letters Patent. Patented Apr. 29, 1919.

Application filed May 21, 1915. Serial No. 29,604.

To all whom it may concern:

Be it known that I, HEINRICH TALLA, residing at Heilbronn-on-the-Neckar, Germany, have invented certain new and useful 5 Improvements in Apparatus for Casting Metals, of which the following is a specification.

The object of the present invention is to provide an improved device for casting metals under an explosion-like pressure into molds. It is a known proceeding to produce such explosion-like pressures by an explosive gas or a mixture of gas and air. The employment of explosive mixtures of gases presents, however, considerable drawbacks. It may suffice to mention, as existing among these drawbacks, the required pipings, non-return and shut-off valves and compression-devices necessary when such gas mixtures are used. The manipulation of the casting devices is troublesome and takes much time and the produced pressure is comparatively small.

A solid or liquid explosive material of any composition is therefore preferably used as the explosion-medium.

The use of a solid or liquid explosive material presents the advantage that all pipings and the like may be dispensed with; that several explosions may be obtained in 30 quick succession; and that the production of castings of larger sizes and of metals comparatively hard to melt may be insured, the output of the plant will be thereby increased and a considerably denser structure of the 35 casting will be attained.

In carrying out the present invention I make use of a casting device provided with a loading space lying in front of the mold and adapted to be shut off from the crucible, 40 whereby the loading space is in open communication with the mold and serves either itself as the space for producing the explosions or to convey the force of explosion, produced in a separate space, connected to the 45 said loading space, into said mold. Two devices for carrying out the process are represented in the drawing by way of example.

Figure 1 shows an embodiment of the invention in a vertical longitudinal section, 50 and Fig. 2 represents another embodiment, also in a vertical longitudinal section.

The device comprises a melting furnace *a* of any appropriate construction with a crucible *b* for storing the metal. The cruci-

ble communicates with a loading space *e* 55 either by a channel *i*, as shown in Fig. 1, or it is, as shown in Fig. 2, directly connected to same. The space *e* is loaded for every single casting operation by the shut-off valve *d* secured to the bar *c*, this crucible and valve 60 being well known forms not constituting specifically any part of my invention.

A lever *h* serves for operating the valve.

For the purpose of loading the molds the space *e* has a channel *f* with a lip for affixing 65 the loading nozzle to the molds. The space *e* communicates, according to the embodiment shown in Fig. 1, by the conduit *g* with a suitable explosion-chamber *k*, or explosive may be introduced through the conduit *g* 70 into the loading space *e*.

With the device according to Fig. 2 the loading space *e* lies immediately under the crucible *b*; the pressure produced by the explosion in the loading space being conveyed 75 through the hollow spindle *c* carrying the valve and the valve *d* itself.

The ignition in the explosion chamber can be obtained in a mechanical way, the same as the opening and closing of the molds, and in 80 due succession.

The operation of the device is as follows:—

As soon as the metal in the crucible *b* has become sufficiently fluid, a certain part of it 85 approximately corresponding to the capacity of the mold is, by lifting the lever *h*, allowed to run into the loading space *e*. An explosion then takes place and the pressure forces the metal through the channel *f* quickly into 90 the mold for the purpose of exactly filling all the hollow spaces in the same.

For producing the explosion, gunpowder is preferably employed and, in a modified form of construction instead of being exploded in a separate chamber, it may be fed through the hollow spindle *c* or the conduit *g* and ignited by the liquid metal so as to force the latter into the mold. A special ignition device may thus be dispensed with. 100

What I claim as my invention and desire to secure by Letters Patent is:—

1. A device for casting metal and the like under an explosion-like pressure into molds, comprising a crucible, a loading space having a channel leading therefrom adapted to communicate with a mold, and means for opening communication between said load-

ing space and the crucible, said loading space being adapted to be placed under the pressure of the explosion.

2. A device for casting metal and the like under an explosion-like pressure into molds, comprising a crucible, a loading space having a channel leading therefrom adapted to communicate with a mold, means for opening communication between said loading space and the crucible, an explosion cham-

ber, and a conduit leading from said loading space to the chamber where the explosion is produced.

In testimony whereof I have signed my name to this specification in the presence of 15 two subscribing witnesses.

HEINRICH TALLA.
